CLAIM

The ornamental design for a creamer and sugar bowl simulating thimble set, as shown and described.

DESCRIPTION

FIG. 1 is a perspective view of a creamer and sugar bowl simulating thimble set showing our new design; FIG. 2 is an exploded perspective view thereof; FIG. 3 is a front elevational view of the sugar bowl thereof;

FIG. 4 is a side elevational view of the sugar bowl;

FIG. 5 is a top plan view thereof;

FIG. 6 is a bottom plan view thereof;

FIG. 7 is a front elevational view of the creamer thereof;

FIG. 8 is a left side elevational view of the creamer;

FIG. 9 is a right side elevational view thereof;

FIG. 10 is a top plan view thereof; and

FIG. 11 is a bottom plan view thereof.
